UNITED STATES PATENT OFFICE.

GUSTAV ADOLPH DOEBBEL, OF ALTONA, GERMANY.

SMOKE-CONSUMING APPARATUS.

SPECIFICATION forming part of Letters Patent No. 727,106, dated May 5, 1903.

Application filed August 29, 1902, Serial No. 121,497. (No model.)

To all whom it may concern:

Be it known that I, GUSTAV ADOLPH DOEBBEL, a subject of the German Emperor, and a resident of Altona, in the Province of Schleswig-Holstein, in the Kingdom of Prussia and Empire of Germany, have invented certain new and useful Improvements in Smoke-Consuming Apparatus, of which the following is a specification.

This invention relates to an improved apparatus or installation for furnaces of all kinds, by means of which the smoke which enters the flues unconsumed may there be burned with useful effect and in such a manner that no smoke enters the chimney or funnel or escapes therefrom into the atmosphere. The said installation is composed of various devices in such a manner and the functions of the same are so connected one with the other and arranged to coöperate or alternate that under the influence of an arrangement of fluid-fuel burners the thin flames or flame-jets of which are uninterruptedly directed into suitable parts of the smoke-flues the smoke is consumed in the flues or in those of them which surround or come into contact with the body to be heated, thus effecting economies in the consumption of fuel, while by one of the said arrangements a greater development of energy is imparted to the draft of the furnace, so that steam may be maintained in the boiler better than heretofore. A further special advantage of this installation consists in the fact that all existing heating and furnace installations may be converted into installations in accordance with this invention without any considerable modification in their operative parts at a comparatively small cost and with but little interruption in their working—for example, during the cleaning of the boilers.

By means of the fluid-fuel burners above referred to it is possible to distribute the combustion of the smoke over the entire length of all the flues up to the chimney, and a subsidiary result of this is that the air is also better distributed throughout the whole of the flues and in larger quantities, so that the air has the force, time, and space to sufficiently commingle the smoke with oxygen and

conduct it into all parts of the flues into contact with the flames of the fluid-fuel burners arranged there, where it is ignited and completely consumed.

In order that my invention may be more fully understood, I shall now proceed to describe the same in detail, and for that purpose reference is taken to the accompanying sheet of drawings, wherein—

Figure 1 is an end view, partly in section on the line I I, Fig. 2, of a stationary Cornish boiler provided with and embodying my invention. Fig. 2 is a longitudinal horizontal section, and Fig. 3 a longitudinal vertical section, of the said boiler; and Fig. 4 is a detailed view showing, on an enlarged scale, a longitudinal section of a fluid-fuel burner.

Similar letters refer to similar parts throughout the several figures.

According to this invention the air may be supplied through appropriate pipes *b*, or said air-supply may be effected in other ways, according to the arrangement of the heating installation, and may, for example, be produced by compression. As the air must always be introduced into the flues between the hearth and the chimney and in closer proximity to the chimney than to the hearth, it prejudicially effects the draft conditions of the furnace in all cases to a greater or less extent, and in order to compensate for this the energy of the furnace must be artificially increased. In the present instance this is effected by forcing compressed air through a pipe *b* and suitable pipes *c* and a series of holes in these latter pipes under the grate between the grate-bars into the fuel, so that it passes through this latter, its oxygen causing an energetic combustion of the fuel and of its smoke even in the furnace and also supporting a further penetration of the flames into the flames-tubes or fire-flues. The stronger and more voluminous this compression is up to a certain limit the greater the quantity of air which may be introduced into the flues without prejudice to the conditions of the draft until complete smoke combustion is obtained, and this without driving the heat into the chimney and out of the same, as the air introduced into the flues al-

ways counterbalances the forcing action of the compressed air under the grate and in the fuel, this being readily effected by means of valves or registers (not shown) on the 5 aforesaid pipes *b* and *c*, the air displacement under the grate or in the fuel being preferably allowed to somewhat preponderate.

As the smoke burns so much the more readily and completely the hotter it is, the 10 air-supply may conveniently be taken from a preliminary heating-chamber, which may be heated by waste steam passing through radiator-pipes or in some other suitable manner. This chamber may be formed of slabs 15 of plaster or the like and be built into the upper masonry of the boiler. This will be unnecessary in most cases, however, if gratings *d*, of iron or stone or of stone in combination with iron, are arranged to as great an 20 extent as is permitted of by the ratio of the draft (considered with reference to the aperture over the fire-bridge, that is) in the flame-pipe or heating-pipes and where possible in the side flues also, which gratings in 25 addition to being heated by the furnace-flames are principally heated and raised to a red or white heat by means of the smoke-gases, which are caused to burn as continuous streams of flame by means of the fluid-fuel burners *a* in all the flues, and which collect the hot air which has hitherto been allowed to escape freely to the chimney and store it up for a longer time for heating the 30 smoke and gradual transmission of its heat 35 to the walls of the boiler or the like.

For the periods following charging of the furnace, when the smoke streams or passes from the cold fuel into the flues in a colder condition, this heating of the grating or other 40 heat-retaining devices distributed throughout the mass is absolutely essential for effecting the complete combustion of the smoke, and its efficiency is so great (as proved by experiments) that after shutting down the fires, 45 owing to the incandescence of these parts if the register of the chimney is opened too soon, the safety-valve of the boiler will be opened and a considerable quantity of steam will blow off. This intense heating of the gratings is of course mainly attributable to the 50 action of the fluid-fuel burners *a* upon the smoke which is permeated with oxygen, which the flames cause to burn continuously, and also to a smaller extent to the result of the 55 action of the energetic permeation of the fuel with oxygen owing to the intense and voluminous supply of compressed air, which causes the furnace-flames, already freed to some extent from smoke, to enter the fire-tubes to a 60 greater distance than has hitherto been the case, thus raising a portion of the grating which starts immediately behind the fire-bridge to incandescence.

The fluid-fuel burners *a* may advantageously be formed in longitudinal boxes *e*, which may be fixed in the masonry, penetrat-

ing into the flues to the desired extent and being open outwardly, Fig. 4. Through suitable piping *f*, in which is arranged a wick *f'*, oil, benzine, or an oil mixture is conducted 70 to the slightly upwardly bent end opening of the pipe and there ignited. Each pipe *f* is provided with a reservoir *g* and may be introduced into the aforesaid longitudinal box *e* when kindled in such a manner that the flame 75 is situated beneath a hole in the box *e*. The flame ascending from the hearth so constituted is drawn into the flues owing to the draft of the chimney, and as thin flame or flame-jet ignites in a continuous manner the 80 previously-heated masses of smoke without being prejudicially affected by the smoke and draft in the flues. The aforesaid reservoir *g* may conveniently be suspended outside. In the case of coal-gas furnaces gas-flames are 85 of course employed instead of the oil-flames described above.

Owing to the fact that, as already explained, an efficient smokeless combustion in furnaces or heating installations cannot in many cases 90 be attained either by means of a single-acting or several single-acting appliances, but only by combining a series of appliances and methods with great care one with the other in such a manner that they act suitably in 95 combination or alternation, these details form an interdependent installation or whole. This novel installation is of special value for steam-generators, owing to the great efficiency obtainable from the fuel, so that owing to economies in fuel, in storage-room, &c., a large saving may be effected.

Having fully described my invention, what I claim, and desire to secure by Letters Patent, is—

1. In a furnace, a grate, a fire-bridge, means to force air beneath the grate, a reverted air-pipe behind the fire-bridge, means beyond the fire-bridge to retain heat, fluid-fuel burners and air-supply pipes in proximity thereto to 110 ignite the products of combustion, substantially as and for the purpose set forth.

2. In a furnace, a grate, a fire-bridge, means to force air beneath the grate, a main flue, a reverted air-pipe and means to store heat in 115 said flue, lateral flues, fluid-fuel burners and an air-supply in proximity to each burner in the lateral flues, substantially as and for the purpose set forth.

3. In a furnace, a grate, a fire-bridge, means 120 to force air beneath the grate, a main flue, a reverted air-pipe and fire-brick gratings in said flue, lateral flues, flame-jet pipes *e* and liquid-fuel-fed burners in said pipes, and air-pipes to feed air in proximity to the flames 125 from said flame-jet pipes, substantially as and for the purpose set forth.

4. In a furnace, the combination with a flame-jet pipe *e* provided with an orifice near its end, a reservoir for liquid fuel, a wick-tube from the reservoir terminating in said pipe near the orifice and auxiliary air-supply

tubes in proximity to the orifice in the flame-jet pipe, substantially as and for the purpose set forth

5. In a furnace, a grate, a fire-bridge, a main flue, an air-supply and heat-retaining gratings in said flue, auxiliary flues, heat-retaining gratings therein, air-supplies and liquid-

fuel burners proximate the air-supplies in the auxiliary flues, substantially as and for the purpose set forth.

GUSTAV ADOLPH DOEBBEL.
